UNITED STATES PATENT OFFICE.

ENOCH PROUTY, OF CHICAGO, ILLINOIS.

EXPLOSIVE-ENGINE.

1,082,237.

Specification of Letters Patent. Patented Dec. 23, 1913.

Application filed January 9, 1908. Serial No. 409,964.

To all whom it may concern:

Be it known that I, ENOCH PROUTY, a citizen of the United States, residing at Chicago, in the county of Cook and State of Illinois, have invented new and useful Improvements in Explosive-Engines, of which the following is a full, clear, concise, and exact description, reference being had to the accompanying drawing, forming a part of this specification.

My invention relates to improvements in explosive engines.

Explosive engines, as heretofore constructed, have necessitated the provision of some means for starting the same by moving the pistons in order that they may take in a charge of explosive mixture. This has been accomplished generally by providing a crank arm by which the operator turns over the crank shaft, moving the pistons so that they will take in an explosive mixture and so that the mixture will be ignited. Another way of accomplishing the same result has been by the provision of some auxiliary power, generally in the form of fluid under pressure, which is admitted to the cylinders for initially starting the pistons.

The object of my present invention is to provide an engine which may be started without cranking and which may be started without the employment of any additional auxiliary mechanism.

I have illustrated, in the accompanying drawings, an explosive engine embodying one form of my invention.

In said drawings, Figure 1 is a side elevation of a two-cylinder explosive engine; Fig. 2 is a sectional view on the line 2—2 of Fig. 1; Fig. 3 is a sectional view on the line 3—3 of Fig. 1; Fig. 4 is a transverse sectional view on the line 4—4 of Fig. 3; Fig. 5 is an end elevation of the engine; Fig. 6 is a transverse section on the line 6—6 of Fig. 3; Fig. 7 is a sectional view taken on the line 7—7 of Fig. 6; Fig. 8 is a detail view of the spark-igniting device; Fig. 9 is a detail of the exhaust and spark-igniting operating cams; Fig. 10 is a detail view of the selective igniting device; Fig. 11 is a section of the feeding-device for the explosive mixture; Fig. 12 is a section on the line 12—12 of Fig. 11; and Fig. 13 is a section on the line 13—13 of Fig. 11.

In the embodiment of my invention, as illustrated in the drawings, I provide a pair

of cylinders 16 and 17 which may be of the usual construction, having the usual water-jacket 18 surrounding the same and mounted upon a suitable support 19. Each cylinder is provided with a piston 20 adapted to be connected with a crank 21 of a crank-shaft 22 by means of a piston-rod 23. The pistons are of the usual construction and a detailed description thereof is unnecessary.

The engine illustrated is of the four-cycle type, and at the upper end of each cylinder there is provided a valve-chest 24, in which are arranged the exhaust and supply valves. The supply valve 25 controls an inlet port 26, which communicates by means of a supply pipe 27 with the explosive charge feeding device 28, a detailed description of which will be given more fully hereinafter. The valve 25 is provided with a valve-stem 29 which extends through the valve casing and has secured thereon a suitable adjustable collar 30, between which and the valve casing is interposed a coiled spring 31 for holding the valve normally closed, the suction of the piston, as the engine operates, being adapted to open the valve. The exhaust valve 32 controls a port 33 communicating with an exhaust pipe 34 leading from the valve-chamber and adapted to communicate with the atmosphere through a suitable muffler, if so desired. The stem 35 of the exhaust-valve extends through the casting forming the chamber, and is provided at its lower end with a suitable cam-face 36. A stop collar 37 is fastened on the stem, and between this collar and the casting is arranged a coiled spring 39 for normally holding the valve 32 seated. The exhaust valve is opened at the proper intervals by means of a roller 40 carried on an upwardly extending arm 41 of a lever 42, which is adapted to be pivoted upon a suitable stationary stud 43. This lever is adapted to be raised by a cam 44 carried on the cam shaft 45 and adapted to bear upon a roller 46 mounted upon the lever 42.

The charge is ignited in the valve-chest by means of a suitable sparking device which comprises a contact 47 which extends into the valve-chamber and at its rear end is supported in position by being passed through by a rotatable shaft 48 which extends through a casting 49 secured upon the exterior of the valve-chamber casting. A pin or lever 50 extends through the shaft 48 and is con-

nnected by a coiled spring 51 with a suitable projection on the casting, whereby the contact 47 is maintained at its lowermost position. The contact 47 is adapted to be engaged by a sparking-contact 52 carried upon the igniting rod 53. This rod extends downwardly through the casting and is provided at its lower end with a collar 54 adapted to be engaged by the movable lever 42. At an intermediate point on the rod is provided a collar 55, between which and the casting is interposed a coiled spring 56 which tends to normally hold the rod in its lowermost position. The lever 42 is raised for moving the ignition-rod 53 by a cam 57, also mounted upon the cam-shaft 45. This cam-shaft preferably extends the whole length of the two cylinders, whereby the respective operating cams for the two cylinders may be mounted upon the same shaft, and is provided at one end with a sprocket wheel 58, over which is adapted to pass a sprocket chain 59 to connect the same with a driving sprocket 60 mounted upon the crank-shaft 22.

The explosive mixture is delivered to the cylinder by means of a mechanical feeding device, which is so constructed that the same sized charge of gasolene is delivered under all conditions by a positive delivery, as distinguished from being drawn out of the supply tank as heretofore, where a carbureter has been used. This mechanical feeding device comprises an in-take pipe 61, which is adapted to be connected with the two supply pipes 27 of the two engines, and which extends downwardly. The lower part of this pipe forms a hood 61^a over the gasolene feeding device 62. The gasolene feeding device 62 preferably comprises a cylindrical member which may take the form of a pipe bored out at its upper end, to form an opening 63 into which is inserted a suitable plug 64. Through the plug is adapted to extend a riser pipe 65, which communicates with a gasolene cup 66 formed in the pipe 62 at the bottom of the plug 64. The gasolene cup 66 is provided with a port 67 communicating with a supply pipe 68 and closed by a suitable valve 69, the stem 70 of which extends downwardly, and at its lower end is provided with a collar 71, between which and the bottom of the pipe 62 is interposed a coil-spring 73 for holding the valve 69 normally closed. The valve-stem 70 is provided with channels 74 to permit a free passage of the gasolene up through the pipe 62 and into the chamber 66. The supply pipe 68 communicates with a pump 75, which is adapted to force the gasolene into the in-take pipe 27. This pump preferably takes the form of a hollow cylindrical member 76, which at its lower end is provided with an opening into which is secured or screwed the end 65 of the supply-pipe 68, and at its bottom with

an opening, into which is secured the end of a pipe 77 which extends to a suitable source of supply. A piston 78 extends down through the central bore of the cylinder 76, and the end thereof stops approximately at the bottom of the opening leading to the supply pipe 68. This piston 78 is raised and lowered through the medium of a stiff arm 79, which extends downwardly along the side thereof and which is provided with a projection 80 adapted to be struck by a cam lever 81 mounted upon the cam-shaft 45 and operated by the cam 82. The arm is preferably pivoted to a cross-arm 83, and at its lower end is connected by a coiled spring 84 with a stationary member 85 mounted upon the frame of the engine, whereby the piston always tends to move downwardly. The throw or downward movement of the piston 78 is regulated by a threaded stop 86, which is adapted to engage one end of the arm 83 and which may be adjusted to any height desired. The supply tank is preferably arranged at a level above the level of the bottom of the pump 76, so that the gasolene level will always be maintained in the bottom of the pump 76 above the top of the supply pipe 68, although any other means of maintaining this level may be provided.

One of the cylinders, which may be preferably the cylinder 16, at a point immediately above the top of its piston 20, when the piston is in its lowermost position, is provided with relief ports 88, which communicate with the muffler 89 of the engine. These ports are preferably bored in the manner illustrated, that is, being bored straight through the cylinder, whereby the exploded gases may escape with the least possible of resistance. These ports are also preferably bored comparatively small, a plurality of the same being provided, and are bored round so that the walls thereof will not tend to cut the piston rings as they pass thereover. The purpose of these parts will appear more fully in the description of the operation of the engine.

For supplying a sufficient quantity of gasolene to prime the engine, I provide a small priming-pump 90, which may be located at any convenient position and communicates by means of a pipe 91 and branch pipes 92 and 93 directly with the valve-chamber of the cylinders. The pipe 91 is provided with a small off-shoot 94, having a suitable cup therein in which a small supply of gasolene may be placed to be pumped into the cylinders by means of the pump 90.

Due to the relative arrangement of the cams for opening of the exhaust valves, the piston of cylinder 16 will always stop on either the in-take or the compression stroke, and the piston of cylinder 17 will always stop on either the explosion or the compression stroke, but the piston of cylinder

17 will never stop on the in-take stroke. When the engine stops with the piston of cylinder 16 leading this piston will be on the in-take stroke. To more fully understand this, we will assume that the engine is running. To stop the engine, the spark circuit is opened. The piston in cylinder 17 moves downwardly on the explosion stroke, and, at the same time, the piston of cylinder 16 moves upwardly on the compression stroke. The momentum of the fly-wheel carries the piston of cylinder 16 over to the explosion stroke, but as no spark occurs the charge is not ignited. However, as the piston of cylinder 17 is now moving on the exhaust stroke, there will be no resistance to the pistons, and expansion of the compressed charge in cylinder 16 will aid the momentum in carrying the piston of cylinder 16 down on its explosion stroke, and up again on the exhaust stroke. While the piston of cylinder 16 is moving on the exhaust stroke, the piston of cylinder 17 is moving on its in-take stroke; and as the piston of cylinder 16 moves off the exhaust stroke and on the in-take stroke, then the piston of cylinder 17 moves on the compression stroke. As the charge in the cylinder 17 is being compressed, it opposes sufficient resistance to prevent the piston from moving all the way over, and the slight expansion of the compressed charge will cause the engine to move slightly backward, thereby assisting in compressing the partial charge taken in by the piston of cylinder 16 on its in-take stroke. As a matter of fact, the pistons slightly teeter back and forth, and, of course, on each downward movement of the piston in cylinder 16 an additional amount of charge is taken in on that cylinder. It will, therefore, be seen from the above, that under these circumstances the piston of cylinder 16 will stop on the in-take stroke and the piston of cylinder 17 will stop on the compression stroke, and be in position illustrated in Figs. 2 and 3. Again, we will assume that the engine is running, and to stop the same, the spark circuit is opened. The piston in cylinder 16 will move on its explosion stroke, the piston of cylinder 17 moving at the same time upward on its exhaust stroke. The momentum will carry the pistons on around, and as the piston of cylinder 16 moves upward on its exhaust stroke, the piston in cylinder 17 will move downward on its in-take stroke, and then move upward on its compression stroke, with piston in cylinder 16 moving downwardly on its in-take stroke. The piston in cylinder 17 has sufficient momentum to pass over and on to its explosion stroke. This brings the piston of cylinder 16 on its compression stroke, which stops the movement of the pistons, and they come to rest in this position,—that is, with

the piston of cylinder 17 having passed on to the explosion stroke and the piston of cylinder 16 on the compression stroke.

In order that the operation of the engine may be understood, it will now be assumed that to start the engine the charge is first ignited in cylinder 16, when the piston thereof is on the in-take stroke. The explosion of the charge drives the piston downwardly, moving the piston in cylinder 17 upwardly on its compression stroke. The exhaust of the exploded charge in cylinder 16 escapes through the relief ports 88, and as the piston in cylinder 17 passes over to its explosion stroke, the charge therein is exploded, and the engine runs in the usual manner. It will now be assumed that instead of the engine having stopped with the pistons of cylinder 16 on the in-take stroke and the piston of cylinder 17 on the compression stroke, it has stopped with the piston of cylinder 17 on the explosion stroke and the piston of cylinder 16 on the compression stroke. To start the engine the charge is ignited first in cylinder 17, driving the piston therein downwardly and moving the piston of cylinder 16 on its compression stroke. As the piston of cylinder 17 starts to move upwardly, it, of course, moves on its exhaust stroke, opening its exhaust valve, and the products of combustion of the exploded charge escape. The piston of cylinder 16 is moved to its explosion stroke and the charge is exploded in the usual way, and the engine continues running. It will therefore be seen from the above that the pistons under all circumstances can be started by simply igniting the spark in the leading cylinder.

The charge to each cylinder is delivered by the feeding device, and this device operates substantially as follows: The piston 78 of the pump 75 being raised by the cam, drops off of the operating cam thereof, and under the influence of the coiled spring 84 drives downwardly with such momentum that a supply of gasoline is forced through the supply pipe 68, raising the valve 69, and the supply of gasoline shoots up through the riser pipe 65 and into the in-take pipes 27 of the two cylinders. As soon as the amount of gasoline which may be forced up by the pump 78 passes through the port 67, the valve 69 is immediately reseated and a further supply of gasoline cannot be delivered, 115 as the coiled spring 73 is of such tension that the suction of the pistons cannot raise the valve. When the piston is moving on the in-take stroke, it draws the air up through the pipe 61, and at the same time draws the supply of gasoline which has been shot into the pipe 65 into the in-take pipes 27, and as the air and gasoline are taken in, the gasoline is thoroughly mixed with the air. As a matter of fact the pump 75 delivers the 130

gasolene with such force up into the in-take pipes 27 that it spatters against the walls thereof, which materially aids in mixing the same with the air, which is drawn in through the pipe 61 by the in-take action of the pistons.

In order, when starting the engine, that the charge shall be first ignited in the leading cylinder, I have provided a means for manually operating the ignition rods and means for preventing this manually operated means from igniting any but the leading cylinder. The manual raising device comprises a rod or cross-bar 95, provided with supports 96 slidably mounted in upright standards 97, whereby the rod or bar 95 may be raised or lowered. Coiled springs 98 tend to hold the rod 95 in its lowermost position, and a cord 99 is provided which is adapted to connect with a handle for raising the rod. As the rod is raised it is adapted to engage the ends of the ignition levers 42, and move the same upwardly to operate the ignition rods. At each end of the rod, however, are provided inwardly extending projections 100 and 101. On the cam-shaft 45 are arranged a pair of cams 102 and 103, the cam or stop 102 corresponding to the position of the crank of the piston in cylinder 16, and the cam or stop 103 corresponding to the position of the crank of the piston in the cylinder 17, so that when the piston of cylinder 16 is the leading cylinder the cam 102 is out of the way of the pin 100, which permits this end of the rod 95 to be raised when the cord 99 is pulled, operating the ignition rod of the cylinder 16. On the other hand, when the cylinder 17 is the leading cylinder, the cam or stop 103 is out of the path of the pin 101, while the cam or stop 102 is in the path of the pin 100, preventing this end of the rod from being raised, and the end of the rod which carries the pin 101 can only be raised to operate the ignition rod of cylinder 17.

While I have throughout the specification, referred to the operating oil as being gasolene, it will be understood that any other suitable hydro-carbon or explosive oil may be used. Furthermore, while I have described my invention specifically with relation to a two-cylinder engine, my invention is applicable to any engine in which the cylinders are a multiple of two.

Having thus described my invention what I claim as new and desire to secure by Letters Patent is:

1. In an explosive engine of the multiple-

cylinder four-cycle type, the combination with a plurality of cylinders, of a plurality of intake ports, a plurality of exhaust ports, valves for said exhaust ports, and a valve controlling mechanism for said valves so arranged that the piston in one cylinder of the engine when said cylinder is the leading cylinder when the engine stops, will stop on the intake stroke, said cylinder having a port arranged therein to be automatically opened at the end of the stroke of the piston to permit the escape of the products of combustion when a charge in said cylinder is exploded with the piston on the intake stroke, to start the engine.

2. In an explosive engine, the combination with a plurality of cylinders, of pistons operating therein, positively actuated means for delivering the liquid hydro-carbon to the engine while the same is running, one of said cylinders having an exhaust port arranged to allow the escape of the products of combustion when a charge is exploded therein with the piston on the intake stroke, to permit the explosion of a charge in the cylinder which happens to be leading when the engine is at rest, and the starting of the engine without cranking.

3. In an explosive engine, the combination with a plurality of cylinders having intake ports, suction valves controlling said ports, pistons operating in said cylinders, a crank shaft having opposite cranks connected to said pistons, one of said cylinders having an exhaust port arranged to allow the escape of the products of combustion when a charge is exploded in said cylinder on the intake stroke, charge ignition means, and a selective means for initially operating said charge igniting means.

4. In an explosive engine, the combination with a plurality of cylinders having intake ports, suction valves controlling said ports, pistons operating in said cylinders, a crank shaft having opposite cranks connected to said pistons, one of said cylinders having an exhaust port arranged to allow the escape of the products of combustion therein, when a charge is exploded in said cylinder on the intake stroke, and selective means for igniting the charge of the leading cylinder.

In witness whereof, I have hereunto subscribed my name in the presence of two witnesses.

ENOCH PROUTY.
